UNITED STATES PATENT OFFICE

2,594,244

CONTAINER FOR LIQUEFIED GASES

Paul F. Winternitz, New York, N. Y., assignor to
Reaction Motors, Inc., Rockaway, N. J., a cor-
poration of New Jersey

Application November 15, 1949, Serial No. 127,423

1 Claim. (Cl. 62—1)

1

The present invention relates to a container or tank for the storage of a liquified gas or other highly volatile liquid. It relates more particularly to a storage tank of this type which is, at the same time, portable and useful for shipping purposes.

An object of this invention is to provide a means of keeping compounds, which are unstable at normal temperatures, at the low temperature of their boiling point where they are stable without the necessity of refrigerating the whole container as is the present practice.

Another object of this invention is to maintain mixtures of liquified gases at a desired composition. Binary mixtures will on evaporation become richer in the component having the higher boiling point and, in many cases, one of the components, when it becomes sufficiently rich, will become highly unstable or even explosive. Mixtures of liquid acetylene and liquid nitrogen or of liquid oxygen and liquid ozone are examples of this. In the latter case for instance it is desirable to maintain the ozone content at about 25% by weight because mixtures containing a greater percentage of ozone are highly explosive. On standing in a conventional container, vacuum bottle type or otherwise, oxygen will evaporate rapidly and the danger limit for the ozone content will be exceeded in a very short period of time. For this reason, it has not been possible to store these mixtures in conventional containers. The present invention solves this problem by keeping the composition of the liquid unchanged by refluxing the boil off in the manner described in this specification.

Another object of this invention is to provide a useful means for permanent storage of low boiling point liquids such as N_2O_4 which has a boiling point of 21.3 degrees centigrade. Such liquids now have to be shipped and stored in heavy steel cylinders because ordinary steel drums will not stand a pressure of 100 to 150 pounds per square inch which may easily be brought about by summer or tropical temperatures. Ordinary ice will be sufficient for refluxing N_2O_4 vapors, in the manner shown in this specification, and accordingly keeping the pressure within the container at a low level. The vacuum container therefore will not have to withstand any appreciable internal pressure and can be constructed of very lightweight material.

A further object of this invention is to provide a storage and shipping container which eliminates both the danger of fire or explosion

2

from escaping vapors and the danger from escaping poisonous fumes by automatically condensing the vapors as they arise into a chilled neck and returning them as liquid to the container through the same neck and without exposure to the atmosphere.

A further object is to provide a shipping container for liquified gases, such as ethane, ammonia and others, of strong, lightweight and economical construction which can be used as a storage vessel without modification.

The present invention meets the requirements of the objects set forth above principally through the use of a refrigerating chamber about the narrow neck of a tank which contains a liquified gas or other volatile liquid, the purpose of this refrigeration of the neck being to chill any vapors arising from the liquid so that they are caused to condense. Because of this effect and the thermal insulation provided for the tank, the pressure created within the entire container is so small that a very lightweight and easily portable structure can be utilized having obvious advantages over conventional heavy high pressure cylinders not having the refluxing feature. Also, the very important proper composition of binary compounds is maintained by these same features as previously pointed out, and expensive and dangerous loss of vapors is prevented since the vessel is closed to the atmosphere except while filling or emptying.

Other objects of the invention will be pointed out in the following description and claims and illustrated in the accompanying drawings, which disclose, by way of example, the principle of the invention and the best mode, which has been contemplated, of applying that principle.

In the drawings:

Figure 1 is a sectional elevation through the container.

Figure 2 is a sectional elevation through a plurality of containers utilizing a common refrigerating chamber.

In Figure 1, a fluid-tight spherical tank 1 of formed thin metal, such as stainless steel, which has a high tensile strength and a low coefficient of thermal conductivity as well as good resistance to corrosion, serves as a container for the liquified gas. A relatively long tubular neck 2 of the same material is welded to tank 1, communicates with it, and extends vertically upward therefrom. At the top end of neck 2 is a hand valve 3 to allow for filling or emptying of tank 1, and a safety rupture disc 4 to allow for relief of pressure within the container in the event

that it should become excessive for any reason such as overheating of the fluid.

Surrounding tank 1 is a spherical jacket 5 formed of the same material as tank 1 but of larger diameter and spaced from tank 1 by 5 means of cork pads 6. A tubular jacket 7 of larger diameter than neck 2 and concentric with it is welded to jacket 5, surrounds neck 2 for a portion of its length, and communicates at its lower end with the space between the walls of tank 1 and jacket 5.

About the exposed end of neck 2 is a chamber 8 having double walls, the inner wall 9 and the outer wall 10. The bottom of chamber 8 is also double, the space between bottoms 11 and 12 15 communicating with that between walls 9 and 10 and that between neck 2 and its jacket 7. The upper periphery of chamber 8 has a ring 13 welded to it to seal off the space between walls 9 and 10 and a wooden cover 14 is provided to close the top of chamber 8. Since all of the welded joints between the various members are airtight, the space between the double walls of tank 1, the double walls of a portion of neck 2, and the double walls of chamber 8 can be evacuated of air. This is done in the present invention in order to create an effective thermal insulation for those parts.

About the entire vessel is an outer protective housing which serves as both further thermal insulation and a physical protection. This housing is composed of a flat bottom 15, a cylinder 16, a frusto-conical portion 17, a smaller diameter cylinder 18, and a ring-like top 19. All of these parts are of thin metal welded together in the manner shown with airtight joints so that all of the space enclosed will be a dead air space and will thus afford additional thermal insulation, and yet this outer housing will be a strong physical protection for the vessel contained within it. Cork pads such as number 20 are provided to support jacket 5 and to space it apart from bottom 15 and cylinder 16. Pads 20 being resilient cork also serve to absorb handling shocks which might otherwise be transmitted to jacket 5 and thus to tank 1.

To use the vessel, it is necessary only to fill refrigerating chamber 8 with solidified carbon dioxide, for example, commonly known as "dry ice," or any suitable refrigerant depending on the boiling point of the liquid to be stored, replace wooden cover 14, which is split on its diameter to allow removal and replacement, fill tank 1 to the lower end of neck 2 with the liquefied gas or other volatile fluid to be stored or shipped, and then close hand valve 3. Neck 2 will thus be chilled and any vapors which may arise from the fluid in tank 1 will pass into neck 2 where they will contact its cold wall thus lowering the temperature of the vapors to the point where they condense to a liquid and flow under the force of gravity back through neck 2 into tank 1. As the condensate flows downward through neck 2, a heat exchange occurs between the condensate liquid and vapors which may be rising into neck 2 resulting in a cooling effect on the vapors and thus making them more easily condensed when they reach the chilled portion of the neck. Also, as the cold condensate drops into the liquid con-

tents of the container, it has a cooling effect thus helping to prevent the formation of new vapors. This condensing, or re-fluxing, continues to take place as long as a refrigerating material is present in refrigerating chamber 8, thus it is only necessary to replenish this to keep the vessel in operation indefinitely. Although a cold material is shown in chamber 8, it is possible to use refrigerating coils or other means of cooling neck 2.

In Figure 2 is shown an arrangement whereby a group of containers is arranged in such a manner that a common refrigerating chamber can be used. Vessels 21, 22, and 23 are arranged in a row with their necks 24, 25 and 26, respectively, extending upward through rectangular chamber 27 which is filled with Dry Ice 28, some other cold material, or refrigerating coils. It is conceivable, also, that containers might be grouped in other geometrical arrangements such as a square, triangle or circle if desirable for convenient shipping and storage of the vessels.

It has been found feasible to ship and store liquid ozone in a vessel of the type represented by the present invention by filling the refrigerating chamber with a very cold substance such as liquid nitrogen.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claim.

What is claimed is:

40 A portable shipping and storage container for liquefied gases comprising a thermally insulated fluid tight vessel, a slender metallic and thin walled single neck communicating with said vessel at one end only and extending upward therefrom, valve means for closing the upper end of said neck, and a thermally insulated cooling chamber integral with said container surrounding at least a portion of said neck whereby said neck is chilled and vapors passing upward into said neck will condense upon coming in contact with the chilled inner surface of said neck and with condensed fluid on the interior of said neck and will then flow as liquid downward through the said neck into the said vessel.
